BICYCLE FORK

James A. Respress, 256 Box Ave.,
Buffalo, N.Y. 14211

Filed Apr. 16, 1973, Ser. No. 351,378

Term of patent 14 years

Int. Cl. D12—11
U.S. Cl. D12—118

The figure is a perspective view of the bicycle fork, showing my new design.

The broken lines in the drawing are for illustrative purposes only.

I claim:

The ornamental design for a bicycle fork, as shown and described.
